Primary Examiner — Charles Hanson

(74) Attorney, Agent, or Firm — Doherty Wallace
Pillsbury & Murphy P.C.(57) CLAIM

The ornamental design for a collar for clothing, as shown and described.

DESCRIPTION

FIG. 1 is a front view of a collar for clothing, showing our new design;

FIG. 2 is a back view thereof; and,

FIG. 3 is an enlarged perspective view thereof.

The broken line showing of the shirt is included for the purpose of illustrating unclaimed subject matter and forms no part of the claimed design.
